UNITED STATES PATENT OFFICE

155,101

DESIGN FOR A CHILD'S TOILET SEAT

Gertrude A. Muller, Fort Wayne, Ind.

Application July 31, 1947, Serial No. 140,640

Term of patent 3½ years

(Cl. D4—5)

To all whom it may concern:

Be it known that I, Gertrude A. Muller, a citizen of the United States, residing at Fort Wayne, in the county of Allen and State of Indiana, have invented a new, original, and ornamental Design for Child's Toilet Seat, of which the following is a specification, reference being had to the accompanying drawing, forming part thereof, in which:

Fig. 1 is a perspective view of a child's toilet seat embodying my new design; and

Fig. 2 is a transverse sectional view of Fig. 1 taken through the mid-section thereof.

I claim:

The ornamental design for a child's toilet seat, as shown.

GERTRUDE A. MULLER.
